UNITED STATES PATENT OFFICE.

WALTER E. HOLLAND, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

BATTERY-CONTAINER CONSTRUCTION.

Application filed June 14, 1921. Serial No. 477,512.

One object of my invention is to provide a novel reinforcing structure for the upper parts of the side walls of built-up or molded containers and especially those made of rubber compound or equivalent material particularly adapted for use in battery construction.

It is further desired to provide a practical, simple and inexpensive container structure for the reception of a removable and replaceable type of handle which shall be securely held in place and prevented from movement up or down, the arrangement being such as to provide substantial support to receive and withstand lateral as well as vertical stresses on the handle.

Another object of my invention is to provide a novel form of reinforcing and handle-receiving structure for the side wall of a battery container, preferably acid-proof and adapted for the reception of a hold-down clamp and also permitting the application of such clamps to properly mounted handles.

These objects and other advantageous ends I attain as hereinafter set forth, reference being had to the accompanying drawings, in which,

Fig. 1 is a side elevation of a molded battery container constructed in accordance with my invention and showing my improved handle as applied thereto.

Fig. 2 is an inverted horizontal section on the line 2—2, Fig. 1, and

Figs. 3 and 4 are elevations showing modified forms of my invention.

In the above drawings 1 represents the bottom, 2—2 the side walls and 3 one of the end walls of an integrally molded or built-up battery container preferably made of hard rubber or equivalent electrolyte-proof insulating material. This container preferably is made with integral plate-supporting ribs 4 projecting upwardly from its bottom 1 and has vulcanized to the upper and outer portions of its opposite end walls two relatively heavy reinforcing plates or blocks 5, though obviously these may be molded as a part of the container body or otherwise firmly attached to the same.

In the present instance each of these blocks extends along the full length of the side wall to which it is applied and of which it forms a part and it preferably, though not neces-

sarily, has its ends bevelled as shown, while 55 its side face may have at its middle a vertically-extending groove or recess 6 for the passage of a hold-down rod. The upper face or edge of the block 5 and a greater or less portion of the top edge of the side wall 3 are 60 indented or recessed as indicated at 7 for the reception of the hook or clamp at the end of said hold-down rod and it is noted that this latter recess preferably is sloped inwardly toward the body of the container to prevent such clamp slipping out of place.

In accordance with my invention the overhanging part of each of the end walls of the container, in the present instance that portion constituted by the reinforcing members 70 5, has formed in it a pair of slots or passages 8, which are oppositely inclined to the vertical so as to downwardly converge. These slots are designed to receive the hooked or transversely extended ends 9 of the side 75 members 10 of a handle 11 preferably made of lead-plated steel or other material inert to or protected from the electrolyte to be used in the battery.

In the present instance the handle is made 80 of relatively heavy wire or rod material which at the center of its top is bent downwardly or depressed as at 12 for the reception of a hold-down clamp in case it should be desired that this engage the handle rather 85 than the container itself. The upper parts of the side portions of said handle, after extending downwardly for a short distance, are bent abruptly toward each other and are then again extended downwardly in substan- 90

tially parallel relation so as to form shoulders 13, their free ends being bent, as shown, in opposite direction and, if desired, their end faces oppositely bevelled. The handle itself is of more or less springy material and 95 the shoulders 13 are so positioned as to lie transversely in and extend laterally beyond the open upper ends of the slots 8 when the upper portions or sides of the outturned ends 9 of the handle engage the underside of 100 100 the overhung reinforcing member 5. Said shoulders thus limit the downward movement of the handle and coact with the ends 9 in limiting or preventing movement of the handle relatively to the container after the 105 handle has been mounted in the position shown.

In mounting the handle its free ends 9 may

be entered respectively in the upper ends of the slots 8 and as said handle is forced down, said ends are forced toward each other by the action of the sloping outer walls of said 5 slots until finally when said ends 9 move out of the lower ends of said slots, they are free to spring apart into engagement with the under sides of the overhung supporting members 5 so as to prevent the withdrawal 10 of the handle. As above noted, the shoulders 13 then prevent the further downward movement of said handle.

Inasmuch as the slots 8 are of substantially the same width as the wire of which the 15 handle is made, there is little if any possibility of lateral movement of the latter. The shoulders 13 in addition to preventing downward movement of the handle beyond its desired position, present relatively extended 20 surfaces for engagement with the upper portions of the sides of the slots, thereby distributing over a considerable wall area any side stresses exerted upon the handle. The handle is inexpensive and easy to manufacture 25 and, in case it should become corroded or otherwise damaged in time, it can be quickly removed and a new one installed. The handle-receiving structure is unaffected by the battery electrolyte and in addition to supporting the handle serves to strengthen and 30 stiffen the container wall of which it forms a part.

Without departing from my invention I 35 may utilize certain of the features of the structure above described without requiring the overhanging block or side projection, for, as shown in Fig. 3, I may form the handle-receiving slots or passages 8 in container walls of the proper thickness and extend

their lower ends laterally as indicated at 8^a 40 to provide retaining shoulders or abutments for the projecting ends or heads 9 of the handle. This may then be mounted or removed as above described.

I may also form the container wall, or the 45 reinforcing block carried by it, with parallel slots or passages 8^a as shown in Fig. 4, in which case the free ends of the handle are forced toward one another by means of a suitable tool to allow of entering said ends in 50 the passages. Upon forcing the handle down the full way, the ends spring outward and the end projections engage the shoulders at the bottom of the passages as in the other cases. 55

I claim:

1. A battery container having a wall provided with oppositely-sloping passages, respectively, having retaining shoulders at their lower ends; with a handle of 60 spring material having extremities movable through said passages and formed to engage said retaining shoulders of the container wall to retain the handles in place.

2. A battery container having a pair of 65 oppositely sloping passages in at least one of its walls; with a handle having preformed projections at its lower ends mounted in said passages.

3. A battery container having in its walls 70 pairs of oppositely sloping passages formed with retaining shoulders; with spring handles each having substantially parallel side members formed with laterally extended ends shaped to coact with the inclined walls 75 of said passages when the side members of the handle are being forced therethrough.

WALTER E. HOLLAND.
